UNITED STATES PATENT OFFICE.

ISIDOR OSCAR NAPP, OF NEW YORK, N. Y.

CONE-WINDING DEVICE.

Application filed November 23, 1925. Serial No. 70,931.

This invention relates to improvements in the art of winding yarn or thread and has especial reference to yarns used for knitting machines wherein the yarn is wound in the form of a truncated cone.

An object of the present invention is to provide means for forming depressions or recesses within the length of the wound cone, so that should breakage of the yarn occur during the winding operation, the knotted portion of the yarn may be placed and kept in these depressions and thus be out of the path of the yarn as the latter is unwound, so that the said yarn will not be caught over the knot and increase the tension on the yarn with a resultant damage to a finished article.

It is therefore the purpose of the invention to provide for a uniform tension of the yarn as the latter is unwound from the cone.

With the above and other objects in view, the invention further includes the following novel features and details of construction, to be hereinafter more fully described, illustrated in the accompanying drawings and pointed out in the appended claims.

In the drawings:

Figure 1 is a fragmentary top plan view illustrating the use of the invention.

Figure 2 is a side elevation of the subject matter illustrated in Figure 1 with a portion in section.

Figure 3 is a fragmentary elevation illustrating a slightly different form of the invention.

Referring to the drawings in detail wherein like characters of reference denote corresponding parts, the reference character 10 indicates a portion of an ordinary yarn or thread winding machine, 11 a portion of a rotatably mounted shaft and 12 a tapered or cone-shaped core or mandrel upon which the yarn is wound, the yarn taking on the shape of a truncated cone as illustrated at 13.

Frequently, during the winding operation the yarn is broken and it is necessary to connect the broken ends by means of a knot so as to continue the winding operation. As a result of this, when the yarn is unwound by a knitting or other machine, the knot will be in the path of the unwinding yarn so that the latter will engage and catch upon the knot. This will increase the tension on the yarn so that the latter is fre-

quently broken, or a stitch is dropped by the knitting machine, with the result of an imperfect place in the knitted article.

The present invention overcomes this disadvantage by providing depressions which are formed during the winding operation to receive the knotted portion of the yarn and to hold the knot or knots in these depressions, so that when the yarn is unwound the knot will be out of the way and the yarn will be unwound in a uniform manner and at a uniform tension.

For this purpose there is provided a shaft 14 upon which is pivotally mounted spaced arms 15. These arms are each shown in Figures 1 and 2 of the drawings as being formed of spaced parallel members which carry at their outer ends rollers 16, while their inner ends are mounted upon the shaft 14 and are held in proper spaced relation by collars 17. The shaft 14 is stationary and rigid with this shaft are arms 17, one of which is provided for each of the arms 15. The arms 18 and 15 are connected by springs 19 which act to force the rollers 16 in yielding engagement with the yarn of the cone 13.

In Figure 1 of the drawings, the arms 15 and their rollers are so spaced as to provide depressions 20 at opposite ends of the cone 13 and when a breakage occurs in the yarn, the knot which is shown at K is placed in the depression nearest the point of breakage and is held therein by the particular roller 16 forming this depression so that it will remain in the said depression during the remainder of the winding operation.

In some types of yarns, for example, mercerized yarns which are of a slippery character, the knotted portions will not remain in the depressions at the ends of the cones and to provide for this relatively close depressions are formed in the cone 13' as indicated at 21 in Figure 3 of the drawings. These depressions are formed by spaced rollers 16' which are mounted within spaced parallel arms 15', the rollers 16' being located between the outer ends of these arms and held in proper spaced relation by a sleeve 22. The arms 15' are mounted for pivotal movement after the manner of the arms 15.

In the form of the invention shown in Figure 3, the knot K is placed in the lowermost depression 21 and when the said knot

slips forward it falls into the upper depression where it remains and is thus out of the way of the yarn when the latter is unwound. Due to the slippery character of mercerized 5 yarn the knot would slip off of the top or bottom of the cone if the knot were placed in depressions similar to those illustrated in Figures 1 and 2 of the drawings.

The invention is susceptible of various 10 changes in its form, proportions and minor details of construction and the right is herein reserved to make such changes as properly fall within the scope of the appended claims.

Having described the invention what 15 is claimed is:—

1. The combination with a yarn winding machine, of means acting upon the yarn as

the latter is being wound to provide annular depressions in the wound yarn.

2. The combination with a yarn winding 20 machine, of pivotally mounted means acting upon the yarn as the latter is being wound to provide annular depressions in the wound yarn and means to yieldingly hold the pivotally mounted means in active position. 25

3. The combination with a yarn winding machine, of spaced pivotally mounted arms, rollers at the outer ends of the arms to engage the yarn as the latter is being wound and means to yieldingly force the rollers 30 into such engagement to provide spaced annular depressions in the wound yarn.

In testimony whereof I affix my signature.
ISIDOR OSCAR NAPP.
